UNITED STATES PATENT OFFICE.

WONG I. GONG, OF NEW YORK, N. Y.

CRANK-HANDLE.

SPECIFICATION forming part of Letters Patent No. 508,218, dated November 7, 1893.

Application filed March 27, 1893. Serial No. 467,679. (No model.)

To all whom it may concern:

Be it known that I, WONG I. GONG, a subject of the Emperor of China, residing in the city and county of New York, in the State of New York, have invented a certain new and useful Improvement in Crank-Handles, of which the following is a specification.

My improvement relates to the crank. It is common to provide a crank-handle of wood, which is capable of revolving on a cylindrical bar of sufficiently stout wire stiffly set in the crank, and constituting the crank-pin. Under the conditions obtaining in the use of clothes-wringers, the metal of this bar oxidizes, and the rust washed therefrom is liable to do much mischief by staining the clothes. Any ordinary plating of metal is liable to be abraded and removed by wear.

I have devised a construction which allows the use of iron or steel for the crank-pin with the great strength which they possess, and allows the water to move freely through the joint between the end of the handle and the crank without allowing the circulation of any water from the wearing part of the crank-pin. Only slight changes are required in the crank and handle.

The accompanying drawings form a part of this specification and represent what I consider the best means of carrying out the invention.

Figure 1 is a front view of an ordinary wringer to which the invention is applied. Fig. 2 is a perspective view of the crank without the pin. Fig. 3 is a section through the end of the crank and the attached handle, with an edge view of the remaining portion of the crank. Fig. 4 is an outline on a larger scale, showing more clearly the peculiarities of the construction at the junction of the handle and the crank-pin with the crank.

Similar letters of reference indicate corresponding parts in all the figures where they appear.

A is the body of the crank, which may be of malleable cast iron, and A', A², is an extension cast integral therewith at the point where the crank-pin is attached.

A² is a button, having a smooth exterior face, and A' a neck considerably smaller, which connects it to the body of the crank A. The rigidly attached crank-pin is marked B.

A head B' on the outer end retains the handle C. The portion B² which is inserted through the crank A, neck A' and button A², is a little smaller than the remainder of the length so that it forms a shoulder which rests firmly against the outer face of the button A², so that on riveting a head B³ on the end of the contracted part it is firmly and permanently held.

In preparing the handle, I bore a cylindrical hole c with a smooth face adapted to receive the neck A' and button A², and make a tight joint against the smooth outer face of the latter. The joint between the end of the handle and the body of the crank A may be open. In the use of the wringer, the water may flow over and about the junction of the handle C with the crank A, and may circulate freely through the joint between the end of the handle C and the cast iron A, and through the cavity c, but it will only come in contact with the cast iron neck A', and the button A². It never gets beyond the tight joint made between the outer face of the button A² and the adjacent wood of the handle. Little rust is formed on the effective part B of the crank-pin, and it can never circulate through the joint and flow inward on the crank or spatter in any manner from the handle so as to get upon and injure the clothes.

Modifications may be made without departing from the principle or sacrificing the advantages of the invention. The neck A' may be contracted or increased in length. The button A² may be slightly enlarged and nicely finished on its periphery so as to make a tight fit piston-wise as well as axially in the smoothly bored and smooth-ended cavity c; but I do not esteem these points essential.

All the metal parts may be galvanized.

I claim as my invention—

1. In a clothes-wringer, the crank A of cast metal, provided with a button A² cast integral therewith, having a smooth outer face, in combination with the handle C having a smooth bottomed recess c receiving such button, and with the crank-pin B having a smaller portion B² extended through the button, all arranged for joint operation substantially as herein specified.

2. In a clothes-wringer, the crank A, smooth faced button A² and smaller neck A', all of

cast iron or analogous strong material not liable to form iron rust, in combination with the crank-pin B having a smaller part B² fitted in the crank, and its neck and button, 5 and headed ends B', B³, and with the handle C having the smooth-bottomed recess c, all arranged for joint operation substantially as herein specified.

In testimony that I claim the invention above set forth I affix my signature in presence of two witnesses.

WONG I. GONG.
